CHAIR

Daniel Forbes Ebbert, Wheeling, W. Va.

Application September 17, 1941, Serial No. 411,174

6 Claims. (Cl. 155—45)

This invention relates to an improved chair, particularly to a chair similar to a beach chair or deck chair which a person may use for relaxing and for sunning himself, or exposing himself to the sun or beneath a sun lamp.

It is an object of this invention to provide an improved chair, the back cradle of which is shaped like the contour of the torso of the human body and will support a person in comfort, either lying on his back or on his abdomen, and which may be used for sunning either the front or back of a person.

A further object is the provision of an improved chair having a reversible cradle portion which, when turned one way, serves to support a person on his back, and when turned in the opposite direction, serves to support a person on his abdomen.

Another object is the provision of a chair having an improved collapsible and adjustable frame in which the frame may be adjusted to various angles, and the frame may be readily collapsed when not in use.

Another object is the provision of a chair in which a person may be seated comfortably and which may readily and conveniently be adjusted to permit the user to recline for sleeping or napping, especially if the person is suffering from asthma or some similar ailment and is prevented from lying in a bed.

With these and other objects in view, reference should be had to the accompanying drawings in which—

Fig. 1 is a plan view of a chair embodying my invention, showing the chair in assembled relationship and with the cradle adjusted to support a person on his back;

Fig. 2 is a longitudinal sectional view in the direction of the arrows on the line 2—2 of Fig. 1;

Fig. 3 is a perspective view of the chair in assembled relationship with the cradle and frame adjusted to a slightly different position from that shown in Figs. 1 and 2;

Fig. 4 is a side view of the chair in collapsed position;

Fig. 5 is a side elevational view of the chair with the cradle supporting member in substantially horizontal position and with the cradle arranged to support a person on his abdomen so as to sun the back of the person;

Fig. 6 is a detail view of the upper portion of the cradle supporting member and cradle frame showing the manner in which they are connected together;

Fig. 7 is a perspective view of the chair with

the cradle supporting member in slightly more elevated position than shown in Fig. 5 and with the cradle arranged to support a person on his back; and

5 Fig. 8 is a perspective view of the chair in upright position in which position it can be used in the manner of an ordinary chair.

My chair comprises, generally, a supporting frame portion 7 and a body-conforming and supporting cradle portion 8, connected to and supported on the frame portion. The cradle portion is so constructed and so connected to the frame portion as to be adjustable or shiftable to support a person in comfort, either on his back or on his abdomen, permitting him to expose either the front or back of his body to the sun or a sun lamp.

The construction of the frame 7 may vary. However, I prefer to employ a frame such as that illustrated, which is adjustable both as to height and as to the angle at which the body is supported. The illustrated frame comprises a pair of front legs 9 and a pair of rear legs 10, pivotally connected together adjacent their upper ends as by means of the hinges 11. The legs may be suitably braced and reinforced by means of the cross braces 12, as shown.

Pivotally connected to an intermediate portion, preferably adjacent the center of the front legs 9, is the cradle supporting member 14, comprising a pair of longitudinal members 14' on the two sides thereof, and a pair of transverse members 15 and 16 adjacent the two ends thereof. The longitudinal members 14' are pivotally connected adjacent their lower ends to an intermediate portion of the front legs, by means of the pins 17. I also provide a pair of arm rests 18 on the two sides of the supporting frame, and these are preferably connected at one end to the longitudinal members 14' by means of the hinges 19.

Adjacent their opposite end, each arm 18 is provided with a sliding connection with a bracket 20 which, in turn, is pivotally connected to the upper ends of the legs 9 and 10 by the hinge 11. The sliding connection between each of the arms 18, and its bracket 20, comprises a guide track 21 having a shiftable shoe or slide 22 disposed therein and which, in turn, is connected to the top of bracket 20.

Due to the construction just described, the legs 10 and 9 may be shifted towards and away from each other to adjust the height of the chair.

Also, the cradle supporting member 14 may be pivotally adjusted so as to vary the angle at

which it is disposed. The adjustment of the several parts results in varying the distance between the hinges 11 and 18. The slideable connection between brackets 20 and arms 18 provides for this variation in distance.

So as to retain the supporting frame in any desired adjusted position, I provide suitable retaining members. Thus, I provide a pair of arms 23 for retaining the legs 9 and 10 in adjusted position, and a pair of arms 24 for retaining the cradle supporting member in adjusted position. The arms 23 are pivotally connected at their forward ends to the front legs 9 by the pins 17, and immediately adjacent the pivotal connection, the arms 23 are preferably provided with arc-shaped portions 26 which facilitate the adjustment of the legs and the collapsing thereof. The rearwardly extending ends of the arms 23 are preferably provided with a plurality of notches 27 extending upwardly from the lower edges, and the notches are adapted to engage with U-shaped loops or brackets 28, secured to the rear legs 10 and through which the arms 23 extend.

The notches 27 are preferably formed with rear walls which are vertically disposed, or which are disposed at a slight forwardly extending angle so as to prevent accidental release of the engagement between the notches 27 and loops 28, in a rearward direction. However, the forward walls of the notches are preferably of cam shape so that the legs 9 and 10 may be pivoted towards each other without interference from the notches 27 and loops 28.

The forward end of the arms 24 are pivotally connected to the upper ends of legs 9 and 10 at the hinges 11. The rearwardly extending ends of the arms 24 are provided with notches 29, similar to the notches 27 and extending upwardly from the lower edges of the arms 24. The arms 24 extend through the loops or straps 30, attached to the longitudinal frame members 14, and the notches are adapted to engage with the pins 31, extending through the straps and which may be in the form of screws for holding the straps in position. The rear walls of the notches 29 are formed similarly to the rear walls of the notches 27 so as to resist accidental release in that direction, and the forward walls are also similar to the forward walls of the notches 27 so as to permit the cradle supporting frame to be pivoted upwardly without interference from the notches.

Thus, it will be seen that the height of the chair and the angle of the back frame may be adjusted as desired, and that they will be retained in adjusted position by means of the arms 23 and 24. The straps 28 and 30 are of such a size as to permit the arms 23 and 24 to be pivoted upwardly with the notches 27 and 29 free from engagement so as to permit ready adjustment of the legs and back frame. When the chair is not in use, the frame may be collapsed in the manner shown in Fig. 4, by pivoting the legs 9 and 10 into contact with each other and by pivoting the back frame upwardly so as to be disposed in substantially the same plane as the front legs 9.

The cradle portion 8 is pivotally connected to the cradle supporting member 14, in a manner which will hereinafter be described, by means of a suitable universal joint, and it preferably comprises a frame 32, extending completely around the periphery of the cradle, and suitable flexible material and padding extending between the

sides of the frame. The frame should be of sufficient strength to support a person, and for this purpose I have found that metal tubing is satisfactory, although other materials, such as wood, particularly bamboo, may also be used. The entire cradle portion including the frame 32 is curved longitudinally concave and convex, on each or both sides, with the maximum amount of curvature being disposed adjacent the lower end, as indicated at 33. In this manner the cradle portion is longitudinally concave near its central and lower end, and convex near its upper end, on one surface, and longitudinally convex near its central and lower end and concave near its upper end, on the opposite surface.

Various types of flexible material may be connected between the sides of the frame so as to serve as the body receiving portions of the cradle. For this purpose, I have found that very satisfactory results are obtained by employing strips of webbing 34, extending longitudinally and transversely of the cradle portion on both surfaces thereof, and extending around the frame 32 at the sides and ends of the cradle portion. Between the webbing on the upper and lower surfaces of the cradle I provide a mat 35 of soft padding material, and for this purpose I preferably employ sponge or foam rubber, although other types of filling and padding material may be employed. Adjacent the upper end of the cradle portion, the two layers of webbing may be stitched or otherwise connected together, as shown at 36, so as to provide a separate head rest or pillow portion 37.

The cradle portion is preferably connected adjacent its upper end to the transverse member 15 of the cradle supporting member. This connection preferably takes the form of a sleeve 38, disposed around the upper portion of the cradle frame 32 and pivotally connected, as at 39, to the upper end of pin 40 which extends through the member 15, and may rotate or pivot with respect thereto. Due to this construction, the entire cradle portion 8 may be pivoted upwardly from its lower end and then rotated, turning the cradle so that either side thereof may be disposed upwardly, thus changing the relationship between the concave and convex portions. The cradle portion 8 and its frame 32 are of sufficient length so that the lower portion thereof rests upon the transverse member 16 of the cradle supporting member.

In using my improved chair, the cradle portion 8 is connected to the supporting frame 1, in the manner described above, and the supporting frame is then adjusted to the desired height and angle. If the user desires to expose the front of his body to the sun, he arranges the cradle so that the side having the lower concave portion is disposed upwardly, and the upper convex portion of the cradle then forms a comfortable support for the back of his body. When he desires to sun the back of his body, he raises the lower end of the cradle portion upwardly and rotates it so that the surface having the lower convex portion faces upwardly, as shown in Fig. 5. The cradle then forms a comfortable support for the front of his body, with the upper concave portion accommodating the chest of the user. The height of the chair and the angle of the cradle supporting frame can be adjusted as desired with the cradle in either position.

As shown in the drawings, the chair may be used in various positions. Thus it may be adjusted to upright position, as shown in Fig. 8,

and used in the manner of an ordinary chair, particularly a lawn chair. It may also be adjusted to substantially horizontal position, as shown in Figs. 5 and 7, and used in the manner of a couch. As shown in Fig. 7, the chair occupies a substantially horizontal position and may be used in this position for comfortable reclining, sleeping or napping.

In Fig. 5, the cradle is arranged so that the user can recline on his abdomen, while in Fig. 7 it is arranged so that he can recline on his back. In Figs. 2 and 3, the chair is illustrated in two different positions for supporting the user in semi-reclining position on his back. Of course it should be understood that when the chair frame is adjusted in the manner shown in Figs. 2 and 3, the cradle may be inverted so as to support the user on his abdomen. When not in use the chair may be conveniently collapsed in the manner shown in Fig. 4.

While my chair is particularly suited for use in taking a sun bath or artificial sun bath, it should be understood that it forms a comfortable chair to be used for any other desired purpose. Thus it may be used as an ordinary chair or as a couch for reclining and resting.

It should also be understood that modifications may be made in the illustrated and described embodiment of my invention, such as changing the construction of the supporting frame on which the cradle is mounted and varying the material from which the cradle is made.

I claim:

1. A chair comprising a frame, a rigid body-conforming and supporting cradle carried by the frame of a length to support the major portion of a human body reclining thereon, said cradle having a longitudinally convex surface and an oppositely disposed longitudinally concave surface, and means connecting said cradle to said frame whereby said cradle may be turned on a longitudinal axis so that either surface of the cradle may be disposed upwardly.

2. A chair comprising a frame, a body-conforming and supporting cradle carried by the frame, said cradle having a surface with a longitudinally convex lower portion for supporting the

front of a body of a person, and a surface with a longitudinally concave upper portion for supporting the back of said body, and means pivotally connecting said cradle to said frame whereby either surface of said cradle may be disposed upwardly.

3. A chair comprising a frame having a pair of front legs and a pair of back legs pivotally connected together adjacent their upper ends and adjustable towards and away from each other to vary the height of the chair, retaining means comprising an arm pivotally connected to one of the pairs of legs and formed with a plurality of notches adapted to have releasable engagement with means attached to the other pair of legs, a back supporting member pivotally connected to the legs adjacent one end, the opposite end being shiftable upwardly and downwardly through an arc with respect to the legs, and means for retaining the back supporting member in the desired position comprising an arm pivotally connected at one end to the legs and formed with a plurality of notches adjacent the other end adapted to have releasable engagement with means attached to the back supporting member.

4. A chair as set forth in claim 3 in which a body-conforming and supporting cradle is attached to the back supporting member.

5. A chair as set forth in claim 3 in which a rigid body-conforming and supporting cradle having a longitudinally convex surface and an oppositely disposed longitudinally concave is attached to the back supporting member by a pivotal connection whereby either surface of the cradle may be disposed upwardly.

6. A chair comprising a frame, a rigid body-conforming and supporting cradle adapted to be supported by the frame, said cradle having one surface adapted to support and substantially conform to the front contour of a human body, and another surface adapted to support and substantially conform to the back contour of said body, and means pivotally connecting said cradle to said frame whereby either surface of said cradle may be disposed upwardly.

DANIEL FORBES EBBERT.
